(57) **CLAIM**

We claim the ornamental design for a bottle, as shown and described.

DESCRIPTION

FIG. 1 is a top, front, left side perspective view of the claimed design;

FIG. 2 is a front elevation view of the claimed design of FIG. 1;

FIG. 3 is a rear elevation view of the claimed design of FIG. 1;

FIG. 4 is a left-side elevation view of the claimed design of FIG. 1;

FIG. 5 is a right-side elevation view of the claimed design of FIG. 1;

FIG. 6 is a top plan view of the claimed design of FIG. 1;

FIG. 7 is a bottom plan view of the claimed design of FIG. 1; and,

FIG. 8 is a left, top, rear perspective view of the claimed design of FIG. 1.

The evenly dashed broken lines in the drawings illustrate the portions of the design that form no part of the claim. The dot-dash broken lines in the drawings define the bounds of the claim and form no part thereof.
